UNITED STATES PATENT OFFICE.

PERCY T. GREENWOOD, OF BRIDGEPORT, CONNECTICUT, ASSIGNOR TO JOHN J. BEIRNE,
OF BRIDGEPORT, CONNECTICUT.

PIPE-WRENCH.

965,890.

Specification of Letters Patent. Patented Aug. 2, 1910.

Application filed August 12, 1909. Serial No. 512,566.

To all whom it may concern:

Be it known that I, Percy T. Greenwood, a citizen of the United States, residing at Bridgeport, in the county of Fairfield and State of Connecticut, have invented certain new and useful Improvements in Pipe-Wrenches; and I do hereby declare the following to be a full, clear, and exact description of the invention, such as will enable others skilled in the art to which it appertains to make and use the same.

My invention relates to pipe wrenches, and has for its object to provide a simple and efficient device of this description which may be readily adjusted and operated, and with these ends in view my invention consists in the combination and arrangement of parts hereinafter fully set forth and then particularly pointed out in the claims which conclude this description.

In the accompanying drawing Figure 1 is a side elevation of my improved wrench—Fig. 2 is a plan view—Fig. 3 is a section at the line x, x , of Fig. 1—Fig. 4 a detail plan view of the stationary jaw, and Fig. 5 a front elevation of the same.

Similar numerals of reference denote like parts in the several figures of the drawing. 1 is the head or body portion of the wrench having formed integral therewith a hand lever 2, and 3 is a stationary jaw which likewise is formed integral with said head. Extending through this head from top to the bottom thereof is a transverse opening 4 within the sides of which are formed guide ways 5, and 6 is the movable jaw which has formed on its rear a rack bar 7 the sides of which are provided with ribs 8 that fit within the ways 5, so that it will be clear that said rack bar will be guided within said ways and will be capable of play.

9 is an opening cut through the head 1 from side to side, the side walls of this opening having cut therein ways 10 shown in dotted lines at Figs. 2 and 4, small gates 11 being cut in one side of said head and leading into these ways 10.

12 is a worm provided at opposite ends with short hubs 13 which latter are introduced through the gates 11 into the ways 10, so that the worm may revolve and at the same time be capable of a lengthwise play within said ways for the purpose presently to be explained.

14 is a block within the opening 9 and

capable of a free movement therein and having its outer face concave and embracing the periphery of the worm 12, and 15 are springs which back up this block and keep the latter normally forced against the worm, whereby the worm will in turn be kept in engagement with the rack bar 7.

The operation of my improvement is as follows:—By turning the worm between the thumb and finger the rack bar will be operated to adjust the position of the movable jaw with respect to the stationary jaw, and the engagement of the worm with the rack bar will be insured by the impact of the spring pressed block 14. By grasping the worm and pulling the same back against the block 14 the worm will thereby be disengaged from the rack bar and the latter may be readily removed if desired; also coarse adjustments of the movable jaw may be effected by disengaging the worm and rack bar and then moving the latter bodily to any suitable position. The ribs 8 on the rack bar have a slight play within the ways 5 so as to permit of a slight back-lash on the part of the movable jaw common in pipe wrenches.

Having thus described my invention what I claim as new and desire to secure by Letters Patent is:—

1. In a pipe wrench, in combination with the head, formed with a stationary jaw, a rack bar at the rear end of the movable jaw, said head being provided with a lateral opening and further provided with grooves or tracks at the opposite sides of said lateral opening, a worm, in engagement with said rack-bar, retaining hubs integral with said worm and operating in said grooves or tracks to allow said worm to be moved toward or away from said rack-bar, a block slidingly mounted within said lateral opening and having its forward face concave and conformably embracing said worm, and spring elements which act against the rear face of said block, said spring elements seating at one end on the rear face of the block and at their opposite ends on the rear end wall of the lateral opening, whereby said worm is normally forced in engagement with said rack-bar.

2. A pipe wrench comprising a head formed with a stationary jaw, a movable jaw carried by the head, said head being provided with a lateral opening extending

through the opposite sides of the head, the
opposite side walls of said lateral opening
being provided with guideways, gateways
on one side of the head which lead into said
guideways, a worm provided with trun-
nions at its ends disposed in said guideways
and adapted to have its trunnions introduced
through said gateways, a block having its
outer face concave to embrace said worm,
springs to engage the rear face of said block
and the rear wall of said lateral opening,
said springs being adapted to force said
block against said worm which latter nor-
mally engages the movable jaw.

15 3. A pipe wrench, comprised of a head, a
stationary jaw, and a movable jaw, said
head being provided with a lateral opening
and with track ways in the opposite side

walls of said lateral opening, gateways in
one side of the head which connect with said 20
slideways, a worm engaging the movable
jaw and having hubs, said hubs being adapt-
ed to be admitted to said slideways through
said gateways, a block contained in said
lateral opening having its outer face con- 25
cave to embrace the periphery of the said
worm and springs adapted to engage the
block to hold same in engagement with the
worm.

In testimony whereof I affix my signature 30
in presence of two witnesses.

PERCY T. GREENWOOD.
